UNITED STATES PATENT OFFICE.

CHARLES H. SCHUH, OF BROOKLYN, NEW YORK.

CATHODE FOR THE ELECTROLYTIC REFINING OF METALS.

Application filed November 22, 1922. Serial No. 602,552.

To all whom it may concern:

Be it known that I, CHARLES H. SCHUH, a citizen of the United States, and a resident of the borough of Brooklyn, city of New York, State of New York, have invented a new and useful Improvement in Cathodes for the Electrolytic Refining of Metals, of which the following is a specification, containing a full and detailed explanation of the principle of the invention and the best manner in which I have contemplated its application.

My invention relates to an improvement in the electrolytic refining of metals, particularly of the metal, copper.

In a co-pending application, Serial No. 589,945, filed Sept. 22, 1922, there is described a device for obtaining an evenly deposited cathode starting sheet of uniform thickness throughout, which may be easily removed from the cathode blank without being torn or injured in any way. These advantageous results are secured by enclosing two metallic sheets within a non-conducting frame, so that one side of the metallic sheets only is exposed to the action of the electrolyte with subsequent deposition of a film of refined metal thereon, by protecting all decreased thicknesses of metal so that even thickness is obtained throughout the deposit and by using preferably what is known as a film-forming metal, so termed in the application, so that the cathode starting sheet is easily stripped off the cathode blank.

The present invention secures all these and the other advantages, described in detail in the above-mentioned co-pending application, combined with certain other important additional features, which are herein described.

My invention consists essentially of enclosing a single-sheet metallic cathode, to be electro-deposited with metal on both sides, whose peripheral edges have been specially formed, so as to afford good fastening and holding properties, with a non-conducting non-metallic frame, fitting tightly around the metallic cathode and being made flush with the surface of the same. To make the joint between the metallic cathode and the non-conducting, non-metallic frame as tight as possible, a little asphaltic or other suitable acid-proof, non-conducting paint is first smeared over the edges of the metallic cathode prior to the fastening thereto of the frame, and then these two parts, namely,

the metallic cathode and the frame, are either riveted together or fastened together with screws. It is also possible to mold the non-metallic frame around the metallic edges by inserting the cathode in a mold and processing in the regular manner.

In order to facilitate the fastening together of the conducting and non-conducting parts of the cathode, the peripheral edges of the metallic cathode and depressions of corresponding form, cut into the peripheral edges of the frame, are shaped in various suitable forms, preferably in the form of a mortice and tenon joint. The shape of these peripheral edges and depressions is immaterial to the purpose of this invention, their sole purpose being to afford suitable connecting and fastening edges between the two parts of the cathode. In the drawing accompanying this application, the preferred shape of the edges is shown.

Similarly it is unimportant for the purpose of this invention just how the metallic cathode and the non-conducting, non-metallic frame are fastened together. The high melting point acid-proof, asphaltic paint, used as described above, may in certain cases provide enough cementing action to make the joint tight enough for all practical purposes, but it is generally preferred to make certain of the tightness of the jointure between the metallic cathode and the non-conducting, non-metallic frame by the use of screws and rivets. The screws may be made of the same material as the frame and similarly the rivets, but if the latter are made of copper, then it is well to use a little non-conducting, acid-proof paint to smear over the exposed surface of the same. It is also possible to mold the plastic materials, that are used in making the non-conducting frame, around the edges of the metallic cathode, and vulcanize or process in other suitable ways the molded frame to produce a hard, solid structure. In this case the holes drilled into the metallic edges of the cathode are filled with the plastic material and both cathode proper and frame are formed into one single, solid piece.

The non-conducting frame may be and is preferably made from hard rubber. The screws and rivets that fasten it to the cathode proper may be and are preferably made from the same material. It is possible to use all sorts of plastic materials and compositions, such as phenol condensation

products, artificial resins of all sorts, artificial rubber compositions, Galalith (a formaldehyde treated casein compound), casein compositions of various sorts, etc. for this purpose.

Particular attention is called to the fact that this form of frame may and can be used with cathodes, made of any metal, metallic composition or alloy. The composition of the metallic part of the cathode is not pertinent, as the frame may be fitted around any shape, form, size or composition of metallic cathode. In all cases the frame is finished off flush with the surface of the metallic cathode, which feature constitutes an important characteristic of this invention. Furthermore, it is important to note that the frame protects all decreased thicknesses of metal, so that even and uniform deposits of metal are secured, which are free from all knobular protuberances. Similarly the effective area of the cathode is made at least as large as that of the anode, so as to avoid the formation of irregular deposits.

The metallic part of the cathode is made preferably from aluminum, aluminum alloy or brass, which avoids the necessity of using graphite and oil compositions to secure an easily and perfectly stripped cathode starting sheet. However, the cathode may be made from copper or any other suitable metal, in which case it may become necessary to use grease, oil and graphite compositions to render it possible to strip off the starting sheet without tearing or otherwise injuring the same.

It is possible to make the cathode from such a heavy metal as lead, preferably alloyed with antimony to the extent of 5 to 10 percent, to make it more resistant to the action of acids, by coating the main body of the cathode, which may be made of aluminum or copper or other suitable metal with an electrolytically deposited coating of lead. This coating may also be secured by mechanical means, casting the alloyed lead on the surface of the aluminum. In this way there is avoided the important disadvantage of the great weight of the lead and there is gained the advantage of the greater resistivity of the lead to the action of the sulphuric acid in the electrolytic bath.

The drawing illustrates by example one way of carrying out this invention, as follows:

Figure 1, is a cathode blank in elevation.

Figure 2, is a plan view of such blank.

Figure 3, is a section on the line 3—3 of Figure 1, showing screw method of fastening the non-conducting frame to the metallic blank.

Figure 4, is a similar section of a modification, showing rivet method of fastening.

Figure 5, is a similar section, showing molded frame secured thereon.

Figure 6, is a section on the line 6—6 of Figure 5.

Figure 7, is a partial plan view of the edge 70 of the metallic cathode, showing cut-out tenon portion.

Figure 8, is a section of the cathode in Figure 1 on the line 3—3, showing metallic cathode with surface coating. 75

In Figure 1 the main body of the cathode, of metallic composition, is shown at 1, the edge at 2 and the fastening device at 3. It will be seen that the fasteners are distributed evenly around the edge, so that the frame is fastened firmly at every point. The jointure between the strips of the frame may be made as indicated in the figure, or else the simple form of mortise and tenon joint may be used. The holes, bored in the cut-out strips at the top of the cathode, are for the purpose of fastening the cathode to the cross-bar on the electrolytic cell. 80 85

Figure 2 is a plan view of the cathode blank, and being self-explanatory needs no further description here. 90

Figure 3 shows the screw method fastening the frame to the metallic cathode. The screw is indicated at 3. 1' indicates the tenon edge of the metallic cathode. Figure 4 shows the rivet method of fastening the frame to the metallic cathode. In this case, when the rivet is made of copper, it will be well to cover the exposed head of the same with a film of acid-proof paint, a non-conductor of the electric current, as shown at 4 in the figure. Figure 5 indicates the molding method of attaching the frame to the edge of the cathode. This is done by well-known methods of attaching plastic compositions to metallic parts. The plate 1 is inserted into a mold permitting material of the shape of the frame 2 to be poured or cast about the tongue or tenon edge. The plastic composition is allowed to harden or set in such mold. The holes, bored in the tenon edge of the cathode plate, are completely filled with the molded plastic composition, so as to give a firm joint between the frame and the cathode proper. 100 105 110 115 3'' shows the filled-in hole.

Figure 6 is a section on Figure 5. The filled-in holes are seen at 3''. 1' indicates the tenon edge of the cathode plate and 2 the frame, fitting around it. 120

Figure 7 is a plan view of the tenon edge of the cathode plate. This edge may be cut out of the formed cathode plate or else the plate may be cast or molded in this form.

Figure 8 shows the cathode plate made up of an aluminum body, 1 and a lead or lead-antimony coating 5. 2 is the frame and 3 the screw fastener, made of the same material as the frame. 125

The term "film-forming metal" is used 130

in the claims to cover such metals as aluminum, aluminum alloys, brass or their equivalents, which are considered to owe their property of formation of easily stripable electrolytic deposits thereon, to the formation of film-forming oxides; and though I 5 preferably claim film-forming metals, I mean to include as equivalent the cathodes having thin non-conducting or non-adherent 10 coatings, such as formed by coating with grease, oil or graphite or combinations thereof, to aid in the formation of an easily stripable deposit.

Having thus described my invention in 15 full detail, I claim as follows:

1. A cathode comprising a plate having a chamfered edge and a frame-work carried by said plate, said frame-work being fastened to said cathode by fasteners, spaced at 20 proper intervals.

2. A cathode comprising a plate having a chamfered edge and a frame-work carried by said plate, said frame-work being fastened to said cathode by fasteners, spaced at 25 proper intervals and cut off flush with the surface of the said cathode.

3. A cathode comprising a plate having a chamfered edge and a frame-work carried by said plate, said chamfered edge being 30 provided with suitably spaced holes, said frame-work being molded around said edge and said holes so as to form a single, solid piece.

4. A cathode comprising a plate having a 35 chamfered edge, said cathode being made of film-forming metal and a frame-work of hard rubber, fastened tightly to the said cathode by suitable fastening devices.

5. A single cathode plate having two main 40 depositing surfaces, non-conducting material about the peripheral edges of said plate, said material being flush with the aforesaid depositing surfaces.

6. A single sheet cathode plate having a chamfered peripheral edge forming a tenon 45 portion, a non-conducting frame about said plate, morticed to fit said tenoned portion and fitting flush with the depositing surfaces.

7. A single sheet cathode plate, as in claim 50 6, in which the tenoned portion is fitted with fastening engaging means, means on said plate coacting with said first-named means securely attaching the frame to said plate.

8. A single sheet cathode plate as in claim 55 6, in which said tenoned part is provided with screw engaging means, screws passing through said frame and said screw engaging means.

9. A cathode plate as in claim 6 in which 60 the metal body thereof is formed of a film-forming metal.

10. A cathode plate as in claim 6 in which 65 the metal body is formed of an aluminum containing body.

11. A cathode plate as in claim 6 in which the metal body is formed of an aluminum core and an acid resisting coating metal.

12. A cathode plate as in claim 6 in which 70 the metal body is formed of an aluminum core and an acid resisting coating metal comprising lead.

13. A cathode plate as in claim 6 in which 75 the metal body is formed of an aluminum core and an acid resisting coating metal consisting of a lead-antimony alloy.

14. A cathode plate as in claim 6 in which the non-conducting frame is rubber.

15. A cathode frame as in claim 6 in which 80 the non-conducting frame is molded hard rubber.
